UNITED STATES PATENT OFFICE.

ENNIS F. HULL, OF SURVEYOR, WEST VIRGINIA.

MAIL-BAG CATCHING AND DELIVERING APPARATUS.

No. 834,662.

Specification of Letters Patent.

Patented April 14, 1908.

Application filed January 17, 1908. Serial No. 411,870.

To all whom it may concern:

Be it known that I, ENNIS F. HULL, citizen of the United States, residing at Surveyor, in the county of Raleigh and State of West Virginia, have invented certain new and useful Improvements in Mail-Bag Catching and Delivering Apparatus, of which the following is a specification.

This invention comprehends certain new and useful improvements in apparatus for delivering and receiving mail to and from railway trains in motion, and the invention has for its object a simple, durable and efficient construction of apparatus of this character which will be positive and sure in its action, capable of being easily manipulated, of light and strong construction and composed of comparatively few parts that may be cheaply manufactured and easily assembled. And a further object of the invention is an improved means for locking the mail bag in the receiving hook after it has once been lodged therein, so as to prevent any rebounding action and insure that the bag, after having once been caught shall not be dropped to the ground underneath the wheels of the train.

With these and other objects in view as will more fully appear as the description proceeds, the invention consists in certain constructions, arrangements and combinations of the parts that I shall hereinafter fully describe and then point out the novel features in the appended claims.

For a full understanding of the invention, reference is to be had to the following description and accompanying drawings, in which:

Figure 1 is a perspective view illustrating my improved mail delivering and receiving apparatus in use; Figs. 2 and 3 are detail top plan views on a larger scale, of the mail receiving or catching hooks, and the improved means with which they are provided to insure the retention of the mail bag after it has once been caught; Fig. 4 is a detail side elevation, with parts in section, of one of the delivering apparatus; Fig. 5 is a similar view illustrating how the parts of said apparatus automatically swing out of the way, as seen as the mail bag has been stripped therefrom by the receiving hook; Fig. 6 is a detail sectional view of the post upon which is mounted the track apparatus of the invention; Fig. 7 is a detail sectional view of the lower end of said post; Fig. 8 is a detail view partly

in section and partly in elevation of one of the fingers for directly holding the rings on the ends of the mail bag; and, Figs. 9 and 10 are detail sectional views hereinafter specifically referred to.

Corresponding and like parts are referred to in the following description and indicated in all the views of the drawings by the same reference characters.

Referring now to Fig. 1, it will be seen that the rod or shaft 1 for supporting the mail receiving devices of the car apparatus is of the usual or ordinary construction, having substantially square ends 2 held removably in the loop keepers 3 at the opposite sides of the doorway of the car. By the particular arrangement of supporting this rod 1, it may be reversed end for end accordingly as the train is moving in one direction or the other, the said rod being provided at one end with a stop collar 4 designed to abut against one of the keepers 3, a pin or other locking device 5 being inserted through the rod upon the opposite side of said keeper, to hold the rod securely in place after it has once been inserted in the keepers.

A sleeve 6 is mounted to turn and slide longitudinally upon the rod 1, and a mail bag receiving or catching hook 7 of any desired type, with the ordinary lodging pocket or loop 8 is secured to the sleeve 6 in any desired way. The sleeve 6 is formed at one end with a recess 9 designed to receive a locking lug 10 formed on a collar 11 adjustably secured to the rod 1 by a set screw as shown, the adjustment of the collar 11 being useful in that it may be turned on the rod and held in proper position to coat with the sleeve 6 in holding the hook 7 properly projected, or at the desired elevation, after the recess 9 has become more or less worn. Another set collar 12 is secured to the rod 1 in the rear of the sleeve 6 and is preferably provided with a buffer 13 of rubber or the like. The sleeve 6 is provided with a handle 14, so that the receiving apparatus may be set with the hook 7 projecting out from the doorway of the car and with the lug 10 engaging the recess 9. When the mail bag enters the hook 7 and lodges in the pocket 8, it is obvious that its impact will slide the sleeve 6 rearwardly on the rod 1 and cause the disengagement of the lug from the recess 9 so that the sleeve may be turned on the rod and the hook swung downwardly and inwardly so as to carry the mail bag within the car. The

rearward movement of the sleeve 6 is limited by the collar 12 and the shock is absorbed by the buffer 13, in an evident manner.

In order to retain the mail bag within the pocket 8 of the hook 7 after it has once lodged therein, I provide a swinging detent 15. This detent in the present instance, is formed of a preferably integral metallic strip bent intermediate of its ends to form spaced parallel members 16 embracing the outer and inner members of the hook 7. The ends of the strip are reversely curved to form hook portions 17. 18 designates the pivot point of the detent 15. Compression springs 19 are secured at one end to the detent 15 eccentrically of the pivot point 18, the other ends of said springs being secured to a pin inserted through ears 20 formed on the sleeve 6.

Referring now particularly to Fig. 2, it will be seen that when the detent 15 is set, the pull springs 19 exert a tension to hold the cross bar of the detent in engagement with the outer members of the hook 7, the members 16 projecting across and in front of the pocket 8, so that they will be struck by the bag as it enters the hook. The springs 19 will thus yieldingly hold the detent 15 in this set position until the bag strikes the detent, whereupon the points of connection of the springs with the members 16 will be turned across the center or rearwardly beyond the pivot point 18, and thereupon the springs will be permitted to exert their tension to snap the hook portion 17 of the detent across the pocket so as to hold the bag, the bag being held securely in the pocket of the hook 7 by the continuing pressure of the springs 19 exerted on the swinging detent 15. This position of the parts is illustrated in Fig. 3 in full lines and in dotted lines is illustrated the fact that the springs continue to exert a tension on the detent after the same has caught the bag, whereby to insure that the bag shall not become accidentally dislodged from the receiving hook 7. If desired, a handle may be formed on this detent 15 to set the same, but I do not regard this as necessary.

In order to provide means for holding the mail bag to be delivered projected out from the car so as to be caught by the track apparatus, I secure to the outer side of the car and to one side of the doorway, as best seen in Figs. 1, 4 and 5, upper and lower brackets 21. A vertically disposed shaft 22 is journaled to swing about a vertical axis in these brackets, the said shaft being provided with laterally projecting upper and lower ends 23, the upper one of which is designed to abut against the shoulder 24 on the upper bracket to limit the movement of the shaft 22 in one direction. The upper and lower bag holding arms 25 and 26 are pivotally mounted on the outer extremities of these ends 23, the upper arm 25 being adapted to swing upwardly, and the

lower arm 26 downwardly, and each of said arms is provided with a horizontally swinging finger 27, the rings of the mail bag 28 being designed to be slipped over said fingers so as to hold the bag suspended. Preferably the pivot studs that connect the fingers 27 with their respective arms are encircled by springs, the tension of which may be regulated by wing nuts 29, as best seen in Fig. 8, so that the ease or freedom of movement of the fingers relatively to the arms shall permit the bag to be stripped therefrom, may be varied.

In order to instantly swing the arms 25 and 26 up and down respectively as soon as the bag 28 has been stripped therefrom I secure a rod or link 30 at its upper end to the upper arm 25 in the rear of the pivot thereof, the lower end of said link being pivotally connected to a rearwardly and upwardly projecting end of the lower arm 26. A spring 31 is secured to this rearwardly extending portion of the arm 26, and another spring 32 is connected to the rod 22, as best seen in Figs. 4 and 5, the tension of these springs exerting an outward pressure on the rear portion of the arm 26 to insure that the same shall be swung downwardly in a positive manner as the upper arm swings upwardly. It will thus be seen that as soon as the mail bag is stripped from the fingers 27 of the arms, the springs will be permitted to exert their tension to swing the arms out of the way to the position illustrated in Fig. 5.

The track apparatus of my invention embodies an upright or post 33 mounted in any desired way along the track, said post being provided at a predetermined point with a collar 34. A sleeve 35 is mounted to turn upon the post 33 with its lower edge resting on the collar 34, and slots 36 are formed by recessing the adjacent edges of the sleeve and collar, a transversely extending latch 37 being accommodated in said slots. A rod 38 within the post 33 is connected at its upper end to the latch 37, and to the lower end of the said rod a foot treadle 39 is connected, said foot treadle projecting out through a vertically elongated slot in the base of the post and being normally held in an upright position by means of a coil spring 40, as best seen in Fig. 7. Under normal conditions, the spring 40 serves to hold the latch 37 in the recesses in the lower edge of the sleeve 35. Upon the attendant depressing the foot treadle 39, the latch 37 is drawn downwardly into the recesses formed in the collar 34 and thereupon the sleeve 35 may be turned on the post so as to reverse the devices which it supports. The sleeve may be provided with a handle 35^a by which it may be turned.

A rod 41 projects horizontally from the sleeve 35, the outer end of said rod supporting a lantern as indicated at 42 so that the track apparatus may be plainly discerned at 130

night, and the sleeve 43 is mounted to slide and turn on the rod 41, said sleeve being provided at its outer end with recess 44 designed to receive a locking lug 45 projecting from the rod.

46 designates a handle by which the sleeve 43 may be set with the hook 47 properly projected.

48 designates a detent similar to the detent 15 above described. The sleeve 35 is formed with lower and upper shoulders 49 designed to support the lower and upper collars 50 and 51 so that the same may be turned thereon, said collars loosely encircling the sleeve above the shoulders so that they may be raised as well as turned. These collars 50 and 51 are connected together for simultaneous movement by a brace 52 and each of these collars is provided with a bearing bracket 53 in which the bag holding arms 54 are mounted for upward and downward movement, respectively, the arms 54 being constructed and arranged like the arms 25 and 26 above described.

25 I have described that my improved track apparatus permits the reversal of the parts by turning the sleeve 35 on the post 33. Obviously a further adjustment is necessary so that the hook 47 and bag holding arms 54 face the track. This requirement is met so far as the bag receiving hook 47 is concerned by duplicating the recesses 44 and locking lugs 45, as best seen in Fig. 9, and by merely giving the sleeve 43, a half rotation on its rod 41. In the case of the bag holding arms 54, this requirement is provided for by the construction and arrangement of the collars 50 and 51 that are mounted to slide up and down and turn around on the sleeve 35 and 40 that are provided with recesses 55 designed for engagement with the locking lugs 56 formed on the sleeve 35. It will thus be understood that after the sleeve 35 has been reversed, the arms 54 may also be turned 45 around on the sleeve 35 so that they will project towards the track. The duplication of the recesses 55 and locking lugs 56 to permit this reversal of the arms 24 is shown in detail in Fig. 10.

50 From the foregoing description in connection with the accompanying drawings, it will be seen that I have provided a very simple, durable and efficient construction of mail bag catching and delivering apparatus which possesses all of the necessary features of adjustability or reversibility, and which may be easily and quickly set in an operative position, the bag delivering parts of the apparatus being quickly and automatically swung 55 out of the way as soon as the bags have been stripped therefrom, the bag catching or receiving parts of the apparatus also swinging quickly and automatically to one side when the bags have been caught therein, and the 60 bags being held securely in the hooks after 65

once having been caught, without any liability of accidental dislodgment.

Preferably the shaft 22 is provided with a spring 22^a that exerts a tension to swing the bag holding arms out from the car or doorway until the upper angular end 23 of the shaft abuts against the shoulder 24 on the upper bracket. The mail car, securing the bag to these arms, will draw the arms into the doorway against the tension of the spring 22^a and as soon as the bag has been attached, will release the bag holding arms and the spring 22^a will thereupon swing the arms upwardly into operative position.

Having thus described the invention, what is claimed as new is:

1. In an apparatus of the character described, the combination with a bag catching hook provided with a pocket, of a detent fulcrumed intermediate of its ends on said hook 55 and adapted to swing thereon so as to project either end across the pocket, a support for said hook, and a compression spring secured to the support and to the detent eccentric of the fulcrum point thereof, as and for 90 the purpose set forth.

2. In an apparatus of the character described, the combination with a bag catching hook provided with a pocket, of a detent comprising an integral strip bent intermediate of its ends to form spaced members pivoted to one arm of the hook and designed to embrace said arm and the opposite arm of the hook, the extremities of said strip being curved to form a hook portion, and means 100 for holding said hook under tension with one end across the pocket and arranged to snap the opposite and hooked portion of the detent across the pocket upon the impact of a mail bag against the first named end of the 105 detent.

3. In an apparatus of the character described, a bag holding device, comprising lower and upper collars formed with brackets, bag holding arms carried by said brackets, a support upon which said collars are mounted to rise and turn whereby the bag holding arms may be reversed in position, and means for locking said collars on their support.

4. In an apparatus of the character described, a bag holding device, comprising lower and upper collars, a brace connecting said collars together, bag holding arms supported by said collars, the collars being arranged to be moved up and down and turned around on their support, a support for said collars, the collars being provided with downwardly facing recesses and the support being formed with locking lugs designed for engagement in said recesses.

5. In an apparatus of the character described, a bag catching hook, a sleeve supporting said hook, a rod on which said sleeve is mounted to turn whereby to project the 130

hook from one side or the other of the rod, means for securing the sleeve on the rod, a vertically disposed sleeve to which said rod is secured, a post upon which said sleeve is mounted to turn, and means for holding said sleeve rigidly on the post.

6. In an apparatus of the character described, the combination of a post, a sleeve mounted to turn on said post, a horizontally disposed rod supported by said sleeve, a bag catching hook reversibly mounted on said rod, and bag holding arms mounted to turn on said sleeve.

7. In an apparatus of the character described, the combination of a post, a horizontally-disposed bag catching hook, a horizontal rod upon which the hook is reversibly mounted, and a support for said rod, the support of the rod being mounted to turn on said post.

8. In an apparatus of the character described, the combination of upper and lower brackets, the upper bracket being formed with a shoulder, a vertically disposed shaft mounted to turn in said brackets and formed with angularly-disposed ends, the upper one of which is adapted to abut against said shoulder to limit the movement of the shaft in one direction, bag holding arms mounted on the ends of said shaft, and spring tension means tending to turn said shaft in a direction to effect the abutment of its upper end with the shoulder.

In testimony whereof I affix my signature in presence of two witnesses.

ENNIS F. HULL. [L. S.]
